EDWARD L. C. CLARK, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

PAPER-FEED-RELEASE MECHANISM FOR TYPE-WRITING MACHINES.

1,163,971.

Specification of Letters Patent.

Patented Dec. 14, 1915.

Application filed July 30, 1910. Serial No. 574,620.

To all whom it may concern:

Be it known that I, EDWARD L. C. CLARK, a citizen of the United States, residing at Middletown, in the county of Middlesex and 5 State of Connecticut, have invented certain new and useful Improvements in Paper-Feed-Release Mechanism for Type-Writing Machines, of which the following is a full, clear, and exact description, such as will 10 enable others skilled in the art to which it appertains to make and use the same.

This invention relates to carriages for typewriting machines, and more particularly to the paper feed mechanism associated therewith.

One of the objects of the present invention is to provide a simple and practical paper feeding mechanism coacting with the platen roller with means whereby the mechanism 20 may be moved out of engagement with the platen roller when it is desired to straighten or adjust the position of a sheet of paper at any time during the operation of the machine.

Another object of the invention is to provide mechanism of the above character whereby all of the paper feeding means associated with the platen roller may be moved out of engagement therewith simultaneously 30 and by a single act of the operator.

A further object is to provide mechanism of the above character which will be easy to operate, cheap to manufacture and efficient in use.

Other objects will be in part obvious and in part pointed out hereinafter.

The invention accordingly consists in the features of construction, combinations of elements and arrangement of parts which 40 will be exemplified in the construction hereinafter set forth, and the scope of the application of which will be indicated in the following claims.

In the accompanying drawings, wherein 45 is shown one of various possible embodiments of this invention, Figure 1 is an elevational view of the platen carriage with parts broken away and other parts removed for the sake of clearness; Fig. 2 is an end view of the carriage with the parts in normal position; Fig. 3 is a partial sectional

view with the feed rollers out of engagement with the platen roller; and Fig. 4 is a plan view of a detail.

Similar reference characters refer to similar parts throughout the different views of the drawings.

As is well known to those familiar with the operation and practical use of typewriting machines, it is frequently necessary to 55 replace a typewritten sheet in the machine in order to make changes or corrections of typographical errors or omissions, and it is quite difficult to replace the paper in its previous relative position to the printing 60 point. This is generally done by inserting the sheet in the usual manner and then actuating certain mechanism to release the feed rollers from their normal engagement with the paper; but this operation still leaves 65 the paper clips and rollers carried thereby in engagement with the paper, so that it is difficult to position the paper without further action on the part of the operator to raise the paper clips. The present invention 70 is intended to overcome the above, among other, objections by providing a single means for simultaneously moving all the paper feeding rollers, paper clips, or other paper holding devices out of engagement with the paper carrier or platen roller, to such an extent that the paper may be 75 adjusted accurately and quickly.

While the present invention is herein 80 illustrated and will be hereinafter described with reference to its application to that form of machine known as the noiseless typewriter, it is, of course, to be understood that the carriage, with the parts carried thereby, could easily be applied to other 85 makes of machines.

Referring now to these drawings in detail, 1 represents a carriage adapted to travel along a shift rail 2 in a well known manner and having the upper part thereof 90 engaging a rigid abutment 3 whereby the pressure of the type carriers, not herein shown, coacting with a flat platen 4 mounted on the carriage adjacent a platen roller 5 will be taken up in a well known manner 95 customary in these pressure-operating machines. The platen roller 5 is suitably trun-

nioned in end plates 6 of the carriage, and its axle 7 is provided with a hand wheel 8 in order to rotate the platen roller.

Pivots mounted on rods 9 secured to the end plates of the carriage are a plurality of sets of brackets 10 carrying pressure rollers 11 normally engaging the platen roller 5 through suitable openings in a paper trough 12. The rear arms of these brackets 10 are normally held down in engagement with an endwise movable bar 13 resting upon the upper surface of the upper guide rail of the carriage by means of pivotally mounted, double arm springs 14. This bar 13 is provided at regular intervals with upwardly bent cam portions 15 which take under the rearwardly extending arms of the brackets 10 when the bar is moved endwise to the left, as shown in Fig. 1, thereby carrying the rollers out of engagement with the platen roller, as shown in Fig. 3. This bar 13 is actuated by means of a wedge-shaped cam 16 carried at one end of a bell crank actuating lever 17. This cam engages a roller 18 carried on the bar 13, and the rear end of the cam 16 is provided with a notch or recess 19, as shown in Fig. 4, thereby to hold the bar in shifted position. The actuating lever 17 is also provided with a cam 20 adjacent its pivotal support, which, with a similar cam at the opposite end of the carriage, engages the under side of supporting members 21 at opposite ends of the platen roller carrying a bar 22 between them upon which are mounted a plurality of paper clips 23. These clips, which are preferably two in number, are laterally adjustable along the bar 22 and are provided with paper feeding roller means 24, each comprising a plurality of rollers of different size, being frusto-conical in shape and having their axes inclined with respect to the axis of the platen roller, thereby to coat with the paper as the same is fed about the platen roller; these rollers serve to remove any intermediate bulge in the paper. The paper clips extend downward over the flat platen 4 in order to hold the paper, and also to catch the edge of the paper as it is delivered 50 from the paper trough 12.

The supporting members 21 are mounted about the axles of the platen roller in such a manner as to permit a radial movement thereof when acted upon by the cam members 20 engaging the under side thereof, as best shown in Fig. 3. This form of connection also permits the bar 22 carrying the paper clips to be rotated partially about the platen roller when in either normal or raised 60 position, as shown in dotted lines, Fig. 3, in order that erasures may be made upon the paper along the upper surface of the platen roller as most convenient to the operator. In order that the supports 21 of the bar 22 65 may be moved in unison, the cams 20

mounted at the opposite end of the platen roller are actuated through a series of links 25 and a longitudinally extending connecting shaft 26, whereby, as the lever 17 is actuated, both cams will rotate simultaneously to raise the supports 21 of the paper clips. 70

The arms 21 carrying the supporting bar for the spring paper clips are held in normal position by means of springs 27, preferably one at each end of the platen roller, engaging pins 28 on the arms 21. In this manner varying amounts of paper may be inserted between the platen roller and the clips, the latter moving bodily with their support when necessary. The paper clips are of sufficient strength normally to maintain a proper pressure upon the paper when the usual two or three sheets are inserted, but should fifteen or twenty sheets be placed 80 upon the platen, the clips and their supports will move bodily away from the platen to accommodate this abnormal amount, and thereby relieve any undue amount of pressure upon the paper. These springs 27 are 85 notched at 29, in order to retain the arms or supports and the attached parts upright and still permit a forward rotation thereof for the purpose above described. 90

The operation and manner of use are substantially as follows: When it is desired to reinsert a sheet of paper in the carriage for the purpose of adding or changing certain impressions thereupon, the sheet is inserted in the well-known manner between the paper trough 100 12 and the platen roller 5 and rolled into substantially the position desired. The usual alining scale or index not herein shown, will indicate to the operator whether or not the paper is in the correct relative position. 105 If the paper is not in the proper position, it may be necessary to move it not only into horizontal alinement, but also with respect to the vertical alinement as well, and in order to do this it is desirable to relieve all 110 pressure exerted thereupon by the paper feeding mechanism. By actuating the lever 17, which can be conveniently done by pressing it back, the lower feed rollers 11 will be carried out of engagement with the platen roller 5, due to the action of the cams 15 engaging the ends of the pivoted brackets 10 in opposition to the pressure exerted thereupon by the pivotally mounted springs 14. Simultaneously the cams 20 will raise the 115 supports 21, carrying therewith the bar 22 supporting the paper clips and paper clip rollers, to substantially the position shown in full lines in Fig. 3. It is then a simple matter quickly and accurately to adjust the paper upon the platen roller, and when the desired position is obtained the operator merely releases pressure upon the lever 17 and the parts are returned to normal position under the action of the several springs. 120 125 130

As above explained, however, the lever 17 may be forced back a sufficient distance to permit the roller 18 to engage the recess 19, whereupon the rollers will be held out of engagement with the platen roller until the lever 17 is pulled forward a sufficient distance to carry the parts 18 and 19 out of engagement. Should the operator desire to make further corrections or erase a word or letter, it will be convenient to move the bar 22 with the paper clips carried thereby around to the position shown in dotted lines in Fig. 3, whereupon the upper surface of the platen roller will make a convenient erasing table.

It is thus seen that this invention provides for a simple and practical device which will be efficient in operation and easy to manipulate, accomplishing, among others, the objects and purposes hereinabove set forth.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In mechanism of the character described, in combination, a platen roller, a bar extending parallel with the same, paper clips carried by said bar, and means for simultaneously moving said bar and clips radially with respect to said platen roller to carry said paper clips out of engagement with said roller.

2. In mechanism of the character described, in combination, a platen roller, a bar extending along above said platen roller, paper clips, and a lever for raising said bar to carry said paper clips out of engagement with said platen roller.

3. In mechanism of the character described, in combination, a platen roller, a bar extending along above said platen roller, paper clips, a lever, and a cam coöperating therewith to raise said bar to carry said rollers out of engagement with said platen roller.

4. In mechanism of the character described, in combination, a platen roller, a bar above said platen roller, paper clips mounted on said bar, supports for said bar, and means coacting with said supports to raise said bar to move the clips out of engagement with the platen roller.

5. In mechanism of the character described, in combination, a platen roller, a bar above said platen roller, paper clips mounted on said bar, supports for said bar,

and a hand lever coacting with said supports for raising said bar and moving the clips out of engagement with the platen roller.

6. In mechanism of the character described, in combination, a platen roller, a bar above said platen roller, paper clips mounted on said bar, supports for said bar, a hand lever near one end of said platen, and means actuated thereby for raising said supports to move said clips out of engagement with said platen roller when said lever is actuated.

7. In mechanism of the character described, in combination, a platen roller, a bar extending along above the same, supports for said bar, paper clips mounted on said bar, a lever, and cams actuated by said lever coacting with said supports to raise said clips out of engagement with said platen roller.

8. In mechanism of the character described, in combination, a platen roller, a bar extending parallel with the same, supports for said bar, paper clips mounted on said bar, a lever, and cams actuated by said lever coacting with said supports to move said clips out of engagement with said platen roller, said clips being adjustable along said bar.

9. In mechanism of the character described, in combination, a platen carriage, a flat platen carried thereby, a platen roller, paper feeding devices positioned above and below said flat platen, a pivotally mounted support for one of said paper feeding devices extending substantially parallel with said flat platen, paper clips adjustable along said support and coacting with said platen roller, and a plurality of cams, one adjacent each end of said flat platen, adapted when actuated to move said paper clips and release the paper feed devices associated therewith.

10. In mechanism of the character described, in combination, a platen carriage, a flat metallic platen extending between the end walls thereof, a platen roller, a pivotally mounted support extending parallel to said flat platen, paper clips carried by said support and coacting with said platen roller, paper feeding devices positioned above and below said flat platen adapted to feed the paper thereover, a plurality of cams, one adjacent each end of said flat platen, adapted when actuated to separate said paper feeding devices, and resilient means adapted to maintain said paper feeding devices in operative relation.

11. In mechanism of the character described, in combination, a platen carriage, a flat platen carried thereby, a platen roller, a pivotally mounted support extending substantially parallel with said flat platen, paper clips adjustably mounted thereon and

1. coacting with said platen roller, paper feeding devices beneath said flat platen for feeding the paper upwardly thereover, a cam adjacent each end of said flat platen adapted when actuated to move paper clips and release the paper feeding devices associated therewith, and springs mounted upon the platen carriage adapted to hold said paper feeding devices and clips in normal position.
5. 12. In mechanism of the character described, in combination, a platen carriage, a flat platen positioned between the end walls thereof, a platen roller, supporting means carried by the carriage, paper clips carried by said support and coacting with said platen roller, rollers carried by said clips, paper feeding means positioned below said flat platen, a cam adjacent each end of said platen adapted when actuated to move said paper clips and release the paper feeding means associated therewith, and a plurality of springs adapted to hold said parts in normal position to resist movement of the parts to released position.
10. 13. In mechanism of the character described, in combination, a platen roller, a pivotally mounted support movable concentrically with respect to the platen roller, paper clips carried by said support, and means adapted to move said support radially with respect to the platen roller for carrying said clips out of engagement with said platen roller.
15. 14. In mechanism of the character described, in combination, a platen roller, paper clips having rollers coacting therewith, supports for said clips, the construction and arrangement of said parts being such that the said clips may be rotated partially about said platen roller, means for holding the said clips in normal position, and means for raising the supports for said clips for carrying the clips and rollers out of engagement with the platen roller.
20. 15. In mechanism of the character described, in combination, a platen roller, paper clips having rollers coacting therewith, supports for said clips, the construction and arrangement of said parts being such that the said clips may be rotated partially about said platen roller, means for holding the said clips in normal position, means for raising the supports for said clips for carrying the clips and rollers out of engagement with the platen roller, and feed rollers coacting with the under side of said platen roller adapted to be moved out of engagement with the platen roller simultaneously with the movement of said paper
25. 16. In mechanism of the character described, in combination, a platen roller, adjustably mounted paper clips coacting therewith, supports for said clips, feed rollers coacting with said platen roller, cam means for simultaneously moving said clips and feed rollers out of engagement with said platen roller, and means whereby said paper clips may be concentrically rotated partially about said platen roller.
30. 17. In mechanism of the character described, in combination, a platen roller, adjustably mounted paper clips coacting therewith, supports for said clips, feed rollers coacting with said platen roller, cam means for simultaneously moving said clips and feed rollers out of engagement with said platen roller, means whereby said paper clips may be concentrically rotated partially about said platen roller, and resilient means for holding said paper clips in normal position.
35. 18. In mechanism of the character described, in combination, a platen roller, a plurality of sets of feed rollers coacting therewith, cam means adapted to remove said feed rollers from engagement with said platen roller, paper clips for said platen roller, supports therefor, cam means coacting with said supports to move the same bodily thereby to remove said paper clips from engagement with said roller, an actuating member, and means for returning said paper clips to normal position.
40. 19. In mechanism of the character described, in combination, a platen roller, a plurality of sets of feed rollers coacting with the under side thereof, cam means adapted to be actuated to remove said feed rollers from engagement with said platen roller, paper clips above said platen roller, supports therefor, cam means coacting with said supports adapted when actuated to move said paper clips bodily from engagement with said roller, an actuating member, and means for returning said feed rollers to normal position.
45. 20. In mechanism of the character described, in combination, a platen roller, a plurality of sets of feed rollers coacting with the under side thereof, cam means adapted to be actuated to remove said feed rollers from engagement with said platen roller, paper clips above said platen roller, supports therefor, cam means coacting with said supports at each end of the roller adapted when actuated to move said paper clips from engagement with said roller, an actuating member, and a plurality of resilient means for returning said parts to normal position.
50. 21. In mechanism of the character described, in combination, a platen roller, a plurality of sets of feed rollers coacting with the underside thereof, cam means adapted to be actuated to move said feed rollers from engagement with said platen roller, paper clips above said platen roller, pivotally mounted supporting means therefor, cam means coacting with said supports

adapted when actuated to move said paper clips from engagement with said roller, a single actuating lever for said cam means, and a plurality of resilient means for returning said parts to normal position, said paper clips being movable partially about said platen roller.

22. In mechanism of the character described, in combination, a platen roller, paper clips coacting therewith, a supporting bar for said clips, and means adapted to

yieldingly hold said parts in normal position, said means permitting said clips and bar to move bodily away from said roller when several thicknesses of paper are used. 15

In testimony whereof I affix my signature, in the presence of two witnesses.
